UNITED STATES PATENT OFFICE

90,661

DESIGN FOR A BABY SEAT

Jacob Kersten, Kalamazoo, Mich.

Application July 5, 1933. Serial No. 48,637

Term of patent 7 years

To all whom it may concern:

Be it known that I, JACOB KERSTEN, a citizen of the United States, residing at the city of Kalamazoo, in the county of Kalamazoo and State of Michigan, have invented a new, original, and ornamental Design for Baby Seats, of which the following is a specification, reference being had to the accompanying drawing, forming a part thereof.

The figure is a perspective view of a baby seat showing my new design.

I claim:

The ornamental design for a baby seat, as shown.

JACOB KERSTEN.
